UNITED STATES PATENT OFFICE.

PHILLIP C. CREEES, OF DECATUR COUNTY, IOWA.

CUTTER-BAR FOR HARVESTERS.

SPECIFICATION forming part of Letters Patent No. 244,435, dated July 19, 1881.

Application filed April 16, 1881. (No model.)

To all whom it may concern:

Be it known that I, PHILLIP CHANNING CREEES, of the county of Decatur and State of Iowa, have invented certain new and useful

5 Improvements in Cutter-Bars for Harvesters; and I do hereby declare that the following is a full, clear, and exact description of the invention, which will enable others skilled in the art to which it appertains to make and use the same, 10 reference being had to the accompanying drawings, and to letters of reference marked thereon, which form a part of this specification, and in which—

Figure 1 is a plan view of my improved cutter-bar for harvesters. Fig. 2 is a similar view, 15 with the individual cutters wholly exposed; and Fig. 3 is a detailed view thereof.

This invention appertains to improvements in cutter-bars for harvesters of that class having a series of separate cutting-teeth, each adapted to be removed for sharpening or for other purposes, having for its object to provide for the ready removal and replacing of the teeth and the holding in a readily-removable manner of the end-securing or false tooth; and it consists of the detailed construction of the individual teeth, and in certain other features, substantially as hereinafter more fully set forth and claimed.

30 Referring to the accompanying drawings, A A' indicate two parallel bars, the underneath one having one end turned up and lapped over the upper one, as at a. The overlapping portion a has an eye, a', to adapt it, in connection with a hook or pintle, to be hinged or pivoted to the harvester. The underneath bar, A, has a series of cleats or separating-plates, b, arranged at intervals apart according to the width of the teeth, as seen in Fig. 2.

40 B B are the cutters, in the form of teeth, tapering each to a point central with its width, as is well known in the art. The sides of the tooth at the base of its sloping edges are parallel, as at c, which fit snugly between two of 45 the cleats b. One of the side edges of the tooth is inclined inwardly a short distance, as at c', and thence extended again straight, as at c''. The opposite side of the tooth is inclined from a point a little higher up than the point of commencement of the incline on the other side,

outwardly about twice the distance as the incline c', as at c³, and thence again extended straight, as at c⁴, slightly greater than the opposite edge, c².

B' is a blunt or false tooth, of somewhat 55 modified construction, with a corresponding extension, c³ c⁴, and a projection or extension, c⁶, on its other side.

It will be noticed that by consulting Fig. 2, with the teeth placed in position as therein 60 shown, the inserting of the teeth being conducted by commencing with the tooth at the outer end of the bar and ending with the tooth B'; each tooth will serve to mutually secure the other in position between the bars A A' 65 and the cleats b without the aid of other fastenings, or the passing of fastening-bolts through the teeth themselves. The advantage of this arrangement is to permit of the ready removal and replacing of the teeth for sharpening, 70 renewal, or other purpose. The plate A' is bolted to the underneath plate after the insertion of the teeth. A spring-plate, C, with one end fastened to the bar A, and its other end provided with an angular aperture, c⁵, is adapted, 75 by springing it over the nut upon the bolt passing through the lapping portion a of the said bar, to prevent the nut turning by jarring or concussion.

Having thus fully described my invention, I 80 claim and desire to secure by Letters Patent—

The combination, with the parallel plates or bars A A', the plate A provided with the cleats or partitions b, of the teeth B B', the teeth B having the inwardly-inclined surface, 85 c', and made straight above and below the incline, as at c and c², on one side, and provided with the greater outward inclination, c³, and above and below this inclination with a straight surface, c⁴ and c⁵, on the other side, and the 90 tooth B' having on each side an outwardly-inclined extension, substantially as and for the purpose set forth.

In testimony that I claim the foregoing as my own I affix my signature in presence of two 95 witnesses.

PHILLIP CHANNING CREEES.
